FEEDING AND CUTTING MEANS FOR
FORMING FASTENERS

André Adler and Robert Adler, Paris, France

Application September 22, 1947, Serial No. 775,550
In France November 7, 1946

3 Claims. (Cl. 164—48)

1

Our present invention relates to a nailing device which is adapted to sever one by one a succession of uniform sections of a wire or a metal strip and to drive them in as they are severed.

The apparatus is particularly applicable for the fixation of window panes into wooden window frames prior to cementing or puttying.

The nailing device comprises shearing means actuated through the medium of a means adapted to cock at the same time and then to release at the end of its stroke a set of springs. The latter is then adapted to actuate, firstly a hammer for driving in the strip or wire section severed by the shears and secondly to feed a wire or strip feeding means as far as a stop arranged at a requisite spacing beyond the shears.

The accompanying drawings illustrate by way of example only, one embodiment of our improved nailing device.

Fig. 1 is a longitudinal cross section along an intermediate plane of the device;

Fig. 2 is a transverse cross section on line II—II of Fig. 1;

Fig. 3 is a horizontal cross section on line III—III of Fig. 1;

Fig. 4 is a separate perspective showing the fastener driver.

Figures 5 and 6 are perspective views showing the fixing of the cover for the strip magazine and illustrate the operation of the device.

Figure 7 is a perspective view of the device illustrating the operation thereof.

As shown in the drawings, the operative mechanism of the nailing device is enclosed in a flat casing formed of a juxtaposed pair of parts 1 and 2. Said casing is formed with wide perforations in its central portion. At its bottom it flares out to form a flat base.

One of the casing portions 1 carries at its rear a circular supply magazine 3 adapted to receive a provision of wire or metal strip stock wound into a flat coil. Said magazine is provided with a cover (not shown) formed with a central aperture into which projects a boss 4 projecting from the bottom of the magazine. Said boss has pivoted thereon strip member 5 adapted to latch the cover in position.

The foremost end of the casing 1—2 contains the movable member or blade 6 of the shear means which blade is adapted to cooperate through the rear cutting edge in its base with the forward upper edge of a fixed anvil 7. The blade 6 is slidably guided by two spacers 8—9 of the casing. The blade is maintained against said spacers by means of a movable stop member 10

2

which is formed with a spring at its top and which in turn is held in position by a pair of pins 11 and 12. The pin 12 is adapted to cooperate with a pair of notches 12a, 12b formed on the push member 13. The back of the movable stop member has a push-member 13 which projects outwards of the casing. Adjacent to its base the stop member is formed with a shoulder or step 14 directed towards the shear means.

The shear means is actuated by means of a hand lever 15 accommodated in the central recess of the casing and pivoted thereto at 15a. Said lever is formed with an upper arm 16 and a lower arm 17. The arm 16 has attached thereto a biasing spring 18 accommodated in the upper part of the casing which forms a grasping handle and is anchored to a fixed projection 18a. The arm 17 has a pin 19 extending therethrough which pin is connected to another pin 20 through links 21, arranged at each side of the member 6. The pin 20 extends through the member 6 through an angular slot 22 having an upwardly inclined portion followed by a longitudinally extending portion.

The ends of the pin 20 extend on both sides of the links 21 and are guided in the longitudinal slides 20a of the casing.

The arm 17 terminates in a nose adapted to engage the upper forward end of a dog 23a pivoted at 23b to block 23 intermediate the lateral extent of said block. The block 23 is longitudinally guided by means of two rods 24 (Figures 2, 3 and 6) at the base of the casing. It is urged towards the arm 17 by springs 25 surrounding the rods 24. A longitudinally extending groove 26a is formed in its bottom face and this groove receives one arm 26 of an L-shaped slide-block 26—27, the upstanding arm 27 of which projects behind the block 23. The slide-block 26, 27 is provided with a longitudinal rod 28 guided in a bore formed in a block 29 pivoted to the casing at 30. A spring 31 surrounds the rod 28 between the block 29 and the slide-block 26—27 to urge the latter forwardly.

The top of the block 23 (Figures 1 and 2) is recessed in the portion thereof intermediate its lateral extent. The dog 23a is pivotally mounted on a transverse pin 23b. It is held in position by the spring 23c and the stop-screw 23d. (Figs. 1 and 3).

The slide-block 26—27 and the block 29 (Figures 1 and 2) are formed with longitudinal splits 32 and 33 respectively opening on the same side of said parts. The side wall of the casing and that of the magazine are each formed with

a split 33a and 33b in alignment with the splits 32—33.

Each of slide blocks 26—27 and the block 29 (Figure 1) are formed with a hole extending from their front face below the splits 32 and 33 and extending into said split at an angle. A spring 34—35 enclosed in said hole acts on a ball 36—37 to urge the latter towards the upper wall of the slit.

Under the block 23 two transverse splits 39—38 (Fig. 2) are formed in a common plane. They are adapted to receive bent-back lugs 39a—39a formed on a fastener driver 39 (Fig. 4) adapted to slide under the bottom face of the casing. The opposite end of said fastener driver has a notch 39b formed therein the width of which corresponds with that of the strip or wire fed to the device. The fastener driver 39 is held in engagement with the block 23 by means of a bottom plate 40 slidably mounted under the bottom of the casing 1—1a. The bottom plate 40 is provided with rubber mountings 41 as shown in Figure 1.

To use the device, the end of the strip or wire contained in the magazine 3 is successively threaded into the slit formed in the block 29 then the slit in the slide-block 26—27 and over the anvil 1, until it engages the stop member 10 see Figure 2. The balls 36—37 do not oppose the movement of the wire or strip in this direction.

If it is desired for instance, to secure a window pane in a wooden window frame, the base of the casing is laid against the pane and the forward of said base is applied against the transverse section of the window frame element involved in the nailing operation. Grasping in one hand the upper part of the casing and at the same time the lever 15, the latter is rocked upwardly. The nose of the arm 17 starts pushing back the block 23 and the slide-block 26—27 which in this direction do not exert any pull upon the wire or strip. At the same time, said arm 17 pulls the links 21 which in turn force the pin 20 along the angular slot 22 of the shear blade 6. This results in a downward movement of said blade which is effective to sever the strip or wire flush with the anvil 1. The severed section of the strip or wire drops into the terminal notch 39b of the driver 39. At the end of the shearing operation, the pin 20 lies in the longitudinal arm of the slot 22 in the blade 6. The latter is therefore arrested from any further downward movement.

Finally, the arm 17 of the lever 16 releases the front edge of the dog 23a. The block 23 is then vigorously projected forward by the sudden release of the springs 25, which together with the fastener driver 39, drives the severed wire or strip section to force it into the frame element worked on.

When the lever 15 is thereafter acted on by biassing spring 18, the arm 17 returns to its position in front of the dog 23a. The dog 23a pivots to allow arm 17 to pass and is ultimately restored opposite to said arm 17 by the action of the spring 23c. At the same time, the slide-block 26—27 follows the block 23, because of the release of the block 31, and carries with it the strip or wire until it abuts against the stop member 10.

When stop member 10 is in the position shown in Fig. 1 the severed section of strip or wire is

shorter, by the full amount of the depth of the shoulder 14, and when said stop member 10 is in its raised position, the end of the strip or wire extends to the inner wall of shoulder 14 so that it becomes longer by the amount of the depth of shoulder 14.

The apparatus instead of being controlled manually may be adapted for mechanical control as for instance with an electric motor or by 10 pneumatic means.

What we claim is:

1. In an apparatus for cutting individual fasteners from a metallic strip and setting them as cut, the combination of a shears comprising a 15 fixed blade having a rectilinear edge and a movable blade cooperating with said fixed blade, a casing, a hand lever pivoted to said casing, and forming an arm with a first pin therethrough, an angular slot having an upwardly inclined portion followed by a longitudinally extending portion in said movable blade, a second pin through said angular slot, longitudinal slides in said casing for the ends of said second pin, and links connecting the first and second pins on each side 20 of said movable blade.

2. In an apparatus for cutting individual fasteners from a metallic strip and setting them as cut, the combination of a cutting means comprising a fixed blade having a rectilinear edge and a 25 movable blade cooperating with said fixed blade, a casing, hand lever means pivoted to said casing and forming an arm with a first pin therethrough, slot means having an upwardly inclined portion followed by a longitudinally extending 30 portion in said movable blade, a second pin through said slot means, slides in said casing for the ends of said second pin, and links connecting the first and second pins on each side of said movable blade.

3. In an apparatus according to claim 1, a first block and a second block longitudinally movable to and from the cutting means, said first block being hollow and having a dog pivoted on a transverse axis, spring means urging said dog upwards, abutment means limiting the outward movement of said dog, a nose at the end of the hand lever means adapted to cooperate with the front end of the dog, said second movable block having one arm guided in a longitudinal groove of said first movable block, means for holding a metallic strip, a passage for said metallic strip in said second movable block, and wedging means in said passage to connect said strip and said second movable block when the latter is moved 45 towards the cutting means.
